UNITED STATES PATENT OFFICE.

EDWIN L. BARBER, OF HENRIETTA, TEXAS, ASSIGNOR OF ONE-HALF TO
MYRON J. AMICK, OF WASHINGTON, DISTRICT OF COLUMBIA.

COMBINED OR CONVERTIBLE TOOL.

SPECIFICATION forming part of Letters Patent No. 393,288, dated November 20, 1888.

Application filed March 14, 1888. Serial No. 267,160. (No model.)

To all whom it may concern:

Be it known that I, EDWIN L. BARBER, of Henrietta, in the county of Clay and State of Texas, have invented certain new and useful 5 Improvements in Combined or Convertible Tools, of which the following is a specification, reference being had to the accompanying drawings.

The object of my invention is to produce a 10 tool which can be converted readily into a large-sized or a small-sized screw-driver adapted for different sizes of screws, and which can also be converted readily into a boring-tool or reamer or awl.

Accordingly, my invention consists in the 15 improved construction and organization of parts hereinafter described, and succinctly specified in my appended claim.

In the accompanying drawings, Figure 1 20 shows an ordinary screw-driver provided with a hole through it, and a small lug or projection upon one side of it. Fig. 2 shows a screw adapted to pass loosely through said hole. Fig. 3 shows an ordinary thumb-nut adapted 25 to fit the thread of the said screw. Fig. 4 shows a longitudinal slotted tool, one end of it being a screw-driver and the opposite end pointed to serve as an awl, a reamer, or a boring-tool, as may be desired. Fig. 5 shows my 30 improved tool complete, the attachment being slid back out of position for use. Fig. 6 shows the attachment in position for use as a screw-driver, and Fig. 7 shows it in position for use as a reamer, boring-tool, or scratch-awl.

Referring to the letters upon the drawings, 35 A indicates a hole through an ordinary screw-driver; B, a small lug or projection; C, a slotted tool, the width of the slot corresponding to the size of the lug B, so that the lug will

project up into the slot sufficiently to prevent 40 the tool C from turning on the screw E as a pivot. This screw E passes through the slot in the tool C and through the hole in the screw-driver and clamps the two together, the cut-away part F of the screw entering the slot of the 45 tool C.

G is an ordinary thumb-nut adapted to fit the screw and clamp the tool C firmly against one side of the screw-driver.

I provide a socket, H, in the end of the 50 screw-driver handle, adapted to receive the point of the tool C and aid in holding the tool in place and prevent its turning on the screw as a pivot when it is out of use.

It will thus be seen that I provide a convenient combined or convertible tool adapted 55 for several uses, which saves the expense of providing several separate tools or instruments.

I am aware that various convertible tools 60 have been heretofore made; but

What I claim as new, and desire to secure 65 by Letters Patent of the United States, is—

The combination of a screw-driver, its blade having a hole, A, and a lug, B, and its handle having in its end a socket, H, with a slotted 70 reversible tool, C, pointed at one end and formed for a screw-driver at the other end adjustably held against one side of the screw-driver by means of a screw and nut and the lug B, and adapted to fit in the socket H when 75 out of use, substantially as set forth.

In testimony whereof I have hereunto subscribed my name.

EDWIN L. BARBER.
